PROCESS OF MAKING HEAVY FUEL OIL

Ernest W. Thiele, Chicago, Ill., assignor to Standard Oil Company, Chicago, Ill., a corporation of Indiana

Application October 19, 1938, Serial No. 235,823

5 Claims. (Cl. 196—50)

This invention relates to the conversion of hydrocarbon oils and particularly to the thermal conversion or pyrolysis of heavy hydrocarbon oils into gasoline. One object of the invention is to convert hydrocarbon oils, particularly intermediate boiling oils of the type of gas oils, into gasoline and fuel oil in a manner to produce gasoline of high knock-rating and more valuable fuel oil of lower viscosity than heretofore produced by cracking processes. However, the process may be operated to give higher yields of gasoline of a knock-rating comparable to that now ordinarily produced. A specific object of the invention is to produce improved heavy fuel oil as a by-product of gasoline obtained by the cracking of mixed base gas oil, said heavy fuel oil having a high heating value combined with a low viscosity and a low pour point.

It has heretofore been proposed to separate heavy hydrocarbon oils into fractions by distillation and then separately convert the fractions. It has also been proposed to separate oils into fractions by the action of solvents. According to the present invention, a heavy oil, for example Mid-continent gas oil, is subjected to solvent extraction, thereby separating it into an extract fraction consisting essentially of aromatic hydrocarbons, and a raffinate fraction comprised of non-aromatic hydrocarbons. The raffinate fraction is then subjected to conversion at an elevated temperature, producing gasoline and a very heavy substantially non-volatile fuel oil whose characteristics make it unsuitable for general use. This fuel oil is then blended with the extract obtained from the original gas oil, whereupon a fuel oil is obtained having the desired characteristics, especially the desired viscosity. The invention will be set forth more fully in connection with the accompanying drawing which forms a part of this specification and which shows diagrammatically one form of apparatus for conducting the process.

Referring to the drawing, gas oil may be charged by line 10 to extraction tower 11 where it is extracted by a suitable solvent introduced by line 12 and/or 19. The gas oil employed may suitably be Mid-continent gas oil of 35.5° A. P. I.

gravity and of the following A. S. T. M. distillation:

	°F.
Initial	478
10%	511
20%	530
30%	543
40%	556
50%	570
60%	586
70%	604
80%	628
90%	670
End point	732

Various solvents may be employed for the extraction such as aniline, nitrobenzene, liquid sulfur dioxide, phenol, monochlorophenol, furfural and other oxygen or halogen containing organic solvents. The operation of tower 11 may be improved by introducing the feed stock through line 10 at a slightly elevated temperature, for example, 100 to 150° F. with nitrobenzene and simultaneously apply cooling means, not shown, to either or both ends of the tower, thus causing a separation of oil from solvent in the end zones which results in a refluxing and fractionating action. The solution of solvent and extracted material is withdrawn from the bottom of tower 11 by line 13 leading to extract still 14 where the solvent is distilled off and recycled by line 15 to condenser 16 and solvent receiver 17 whence it flows by pump 18 and line 19 back to the extraction tower 11. The extract oil substantially free of solvent is withdrawn by line 20 for use as hereinafter described. The amount of extract separated depends on the character of the gas oil charged to the extraction tower 11. It will vary within the range of 5% to 30% and usually will fall within the range of 7% to 15%.

The raffinate or gas oil fraction undissolved by the solvent is conducted by line 21 to raffinate still 22 wherein solvent is distilled off by line 23 and the raffinate substantially free of solvent is conducted by line 24 and pump 25 to cracking furnace 26. Here the oil is heated to a high temperature within the cracking range, e. g. 900 to 1100° F. whereby a substantial part of it is converted to gasoline and other light hydrocar-

bons. Because of the effect of the solvent on the gas oil charged to the system, I am enabled to operate cracking furnace 26 at a higher temperature than normally employed in gas oil cracking practice. Even at normal cracking temperatures, however, in the range of 925 to 950° F., I find that the raffinate oil which has been treated with the solvent will crack at a higher rate so that a higher percentage of cracking per pass through furnace 26 is obtained than in the case of ordinary cracking stocks which have not been solvent treated. For example, at a single pass, I may convert 20 to 40% of the gas oil charged to furnace 26, including the oil which is recycled, into gasoline having a boiling range of about 80° F. initial to 400° F. end point. The oil vapors from furnace 26 are conducted by line 27 to evaporator 28. If desired, additional cracking may be obtained by passing the hot vapors through soaking drum 29 before passing to evaporator 28.

As a modification of my process, I may employ cracking catalysts, for example, by substituting in soaking drum 29 a catalyst chamber containing a suitable granular solid catalyst for effecting increased conversion of gas oil into gasoline. Suitable catalysts for this purpose are fuller's earth or bentonite clay, preferably activated by treating with acid, aluminum oxide, preferably deposited on a suitable support such as kieselguhr or silica gel, copper oxide, cadmium oxide, thorium oxide, etc. The oxides or hydroxides of these metals may be deposited on the silica by "adsorbolysis," i. e. hydrolysis by adsorption. When employing a catalyst, it is necessary to regenerate it at intervals by blowing with air to oxidize carbonaceous material deposited thereon.

No heavy tar is produced by the catalytic cracking operation but a refractory heavy oil is obtained which I may blend with the extract obtained from the feed stock to produce the desired fuel oil. Thus, when employing a catalyst in conjunction with cracking furnace 26, I may withdraw a relatively light fuel oil from evaporator 28 by line 30 and blend it with extract in mixer 64, said extract being introduced by line 66 directly as obtained from the charging stock or by line 63 after it has been subjected to cracking. A cracking temperature of about 850 to 1000° F. is usually satisfactory for catalytic cracking and pressures of the order of 10 to 50 pounds per square inch may be employed. Gasoline obtained from the catalytic cracking operation has a higher anti-knock value than when no catalyst is used. For example, it may have an octane number of 80 to 85 instead of 70 to 75 usually obtained without catalyst.

In evaporator 28, sufficient cooling occurs to separate from the cracked vapors a very heavy residue or tar which is withdrawn by line 30. In the case of non-catalytic cracking this tar will usually have a viscosity of about 400 to 1000 sec. furol at 122° F., according to my process. The vapors are conducted by line 31 to fractionator 32 where all hydrocarbon constituents heavier than the desired gasoline are separated and recycled to the cracking furnace 26 by line 33 and pump 34. Vapors or gasoline and gases are conducted by line 35 to condenser 36 and thence to receiver 37. Uncondensed gases are eliminated from the system by line 38. The gasoline is then conducted by pump 39 and line 40 to stabilizer tower 41 where undesired gases are fractionated from the gasoline which is withdrawn by line 42. The gases, consisting chiefly of propane and pro-

pylene, together with smaller amounts of C₄ hydrocarbons, ethane and ethylene, are withdrawn by line 43, condensed in condenser 44 and collected in receiver 45. The liquefied gases from receiver 45 are withdrawn by pump 46 and line 47 through which they may be recycled to the cracking furnace 26 wherein they are further converted (gas reverted) into the desired gasoline or a part or all of the "propane" may be withdrawn from the system by line 48.

Instead of passing the raffinate from still 22 through the furnace 26, a portion or all of it may be conducted by line 49 directly to evaporator 28 where it is partially converted into gasoline by the heat of the vapors from furnace 26 and at the same time it acts to cool the vapors and condense out the desired amount of residue or tar withdrawn by line 30.

A portion of the gas oil from line 10 may also be conducted to evaporator 28 by lines 50 and 49, the amount being regulated to prevent over contamination of the solvent refined stock undergoing cracking therein. Raw gas oil thus introduced into evaporator 28 is partially cracked and distilled therein and ultimately recycled by line 33 to cracking furnace 26, where it is mingled and cracked with raffinate oil from 22.

The extract fraction of the gas oil charged to the system is withdrawn from still 14 by line 20 and forced by pump 51 to cracking furnace 52 where it is rapidly heated to conversion temperatures of the order of 850 to 975° F. The products of conversion are conducted by line 53 to fractionator 57 wherein gasoline and lighter hydrocarbons are removed by vapor line 58 leading to condenser 59 and receiver 60. The condensate is then withdrawn from receiver 60 by pump 61 and line 62 leading to stabilizer 41 where the desired gasoline is separated as hereinbefore described. The residue in the bottom of fractionator 57 is withdrawn by line 63 leading to fuel oil blending tower 64. The heavy products from evaporator 28 and fractionator 57 are combined in tower 64 to produce the desired fuel oil which is withdrawn from the tower by line 65. The viscosity of the very heavy tar from evaporator 28 is thereby reduced to the viscosity desired in the fuel oil. This may be regulated by withdrawing stock at 63a, by regulating the extractor 11 to give more or less extract or by passing more or less stock through line 50. In addition, I may further reduce the viscosity of the tar from evaporator 28 and fractionator 57 by introducing a regulated amount of gas oil extract by line 66.

Heretofore attempts to crack gas oil charging stock extensively to produce maximum gasoline yields has resulted in the production of a tar of very high viscosity and low A. P. I. gravity. At the same time, extensive cracking has occasioned much difficulty with coking of heater tubes. In order to make a satisfactory marketable fuel oil from the heavy tar, just mentioned, it has been necessary to blend it with lighter stocks which were in themselves valuable as potential gasoline producing material. By my process, I select by 65 solvent extraction those constituents of the gas oil charging stock which, because of their aromatic nature, produce little or no gasoline when subjected to cracking. I then conduct the cracking operation in such a manner that a very heavy 70 tar is produced which is unmarketable as fuel oil and I combine this tar with the aromatic extract previously separated to produce a fuel oil having a viscosity below 250 sec. furol at 122° F. As an example, I may conduct the operation of 75

furnace 26 to produce a fuel oil in evaporator 28 having viscosity of 794 seconds furol at 122° F. and thereafter blend sufficient light fraction by line 33 to reduce the viscosity to 175 sec. furol at 122° F., thus making it satisfactory for use in atomizing fuel burners. The amount of light fraction from fractionator 51 required for reducing the viscosity to this extent is about 10%. A larger or smaller amount of the light fraction 10 may be introduced, depending on the character of the fuel oil required. Thus, the blended fuel oil product may have a viscosity of 100 to 200 sec. furol at 122° F. It is generally desirable that the viscosity be less than 250 sec. furol at 122° F. 15 The effect of combining extract from line 66 with tar from evaporator 28 is shown by the following table:

Amount of extract introduced	Viscosity of the blend-furol at 122° F.
None.....	794
10%.....	213
20%.....	71

25 The pressure employed in the cracking operations conducted in furnaces 26 and 52 may be varied over a considerable range, for example, from 50 to 1000 pounds per square inch. However, I prefer to employ pressures of the order of 30 400 to 750 pounds per square inch at the outlet of furnace 26 and 50 to 200 pounds at the outlet of furnace 52, and reduce the pressure in evaporator 28 and tower 51 to between 50 and 200 pounds per square inch.

35 Although I have described the recycling of liquefied normally gaseous hydrocarbons from receiver 45 to cracking furnace 26, I may also employ gas reversion in cracking furnace 52. For this purpose liquefied gases may be conducted 40 from pump 46 by valved line 54 to the inlet of the coil in furnace 52 wherein the liquefied gases, e. g. liquid propane or propylene, together with other liquefied gaseous hydrocarbons, such as 45 ethane, ethylene, butane and butylene, react with the extracted oil from tower 44 to produce higher yields of gasoline and reduce the tendency of the extract oil to produce coke in heater 52.

Although I have described my process with respect to certain embodiments thereof, I intend 50 that it be limited only as set forth in the following claims:

I claim:

55 1. The process of converting gas oil cracking stock into gasoline and merchantable fuel oil which comprises separating said gas oil stock by the action of a selective solvent into a raffinate and an extract fraction, subjecting the raffinate

fraction to cracking at a high cracking temperature between 900 and 1100° F., separating the cracked products into heavy tar having a viscosity of about 400 to 1000 seconds furol at 122° F., cycle oil, gasoline and gaseous hydrocarbon 6 constituents, recycling the said cycle oil to said cracking operation and reducing the viscosity of said heavy tar by combining therewith a sufficient amount of said extract fraction to produce the desired merchantable fuel oil. 10

2. The process of converting heavy hydrocarbon oil stock into gasoline and heavy fuel oil which comprises separating said hydrocarbon oil stock by the action of a selective solvent into a raffinate and an extract fraction, subjecting the 15 raffinate fraction to cracking at a high cracking temperature between about 900 and 1100° F., separating the cracked products into heavy tar having a viscosity between about 400 and 1000 seconds furol at 122° F., cycle oil, gasoline and 20 gaseous hydrocarbon constituents, recycling the said cycle oil to said cracking operation and blending with said heavy tar sufficient of said extract fraction to reduce the viscosity below about 250 seconds furol at 122° F. 25

3. In the process described in claim 1 the additional step of subjecting the said extract fraction to once through cracking without recycling before combining with said heavy tar to reduce the viscosity thereof. 30

4. In the process of converting gas oil into gasoline and a desirable fuel oil having a viscosity below 250 sec. furol at 122° F. wherein the cracking operation is conducted under conditions to produce a maximum yield of gasoline 35 and concurrently a tar of viscosity above 250 sec. furol (122° F.) for fuel oil, the improvement comprising initially separating said gas oil by means of a selective solvent into a raffinate fraction and an extract fraction, cracking said raffinate fraction at a temperature between about 900 and 1100° F., evaporating the cracked products to separate therefrom a tar having a viscosity above 400 sec. furol at 122° F., fractionating the desired gasoline from the remaining 45 vapors and recycling to said cracking operation intermediate boiling cycle oil and combining with said tar a regulated amount of said extract fraction to produce a fuel oil having a viscosity within the range of about 100 to 250 sec. furol at 50 122° F. 50

5. In the process of claim 4 the additional step of subjecting said extract fraction to once through cracking without recycling before combining it with said tar to produce said fuel oil 55 having a viscosity within the range of about 100 to 250 seconds furol at 122° F.

ERNEST W. THIELE.
